UNITED STATES PATENT OFFICE.

ALBERT C. LUDLUM, OF NEW YORK, N. Y., AND ARTHUR LOWY, OF NEWARK, NEW JERSEY, ASSIGNORS TO NATIONAL BUSH COMPANY, A CORPORATION OF NEW YORK.

APPARATUS FOR SETTING BUNG-BUSHINGS.

1,244,997.

Specification of Letters Patent. Patented Oct. 30, 1917.

Application filed April 14, 1916. Serial No. 91,164.

To all whom it may concern:

Be it known that we, ALBERT C. LUDLUM and ARTHUR LOWY, citizens of the United States, residing at New York, in the county 5 of New York and State of New York, and Newark, in the county of Essex and State of New Jersey, respectively, have invented certain new and useful Improvements in Apparatus for Setting Bung-Bushings, of which 10 the following is a full, clear, and exact specification.

This invention relates to apparatus for setting bushings in bung holes of barrels and the like. The object of the invention is to 15 provide a hand operated device comprising a novel form of bushing setter with means for holding it in operative relation to the barrel and bushing.

It is the object of the present invention to 20 provide a simple, inexpensive and easily portable apparatus, which will be readily positioned for operation and which will turn over the flange on the bushing with an economy of attention and effort not attainable 25 by prior devices. With this end in view, the bushing setter of this invention comprises an outer sleeve portion stationary on the bushing and holding it against turning moments and an inner relatively rotatable spindle carrying flanging rollers at the ends of pivoted 30 flanging arms, which automatically position the rollers relatively to the work. This automatic control of the operation of the rollers is particularly useful where the setting operation is carried on out of sight of the operator as is usually the case in setting bung bushings.

A further object of the invention is to support the setter with relation to the barrel 40 and to fasten it in place on the bushing. For this purpose a stand is provided for the barrel and the setter is fastened to the stand and held down on the bushing by link members connecting the setter to the stand and 45 adjustable in tension to hold the parts rigidly together. By this means the barrel is held in place on the stand and the outer sleeve of the setter is pressed against the bushing and holds it from rotating in the 50 barrel.

By these means the setter and barrel are easily positioned and are held in proper operative relation by the fastening means so that the operator can devote his entire at- 55 tention and effort to the operating of the

flanging spindle. When completed, the setter can be lifted up out of the way until again required.

In the accompanying drawings showing 60 an embodiment of the invention,

Figure 1 is a vertical section of the setter in operative position;

Fig. 2 is an end view of the barrel and setter in position on the stand, and

Fig. 3 is a detail of the clamping means. 65

The setter is illustrated in Fig. 1 in operative position in bushing B of barrel A. The outer sleeve 1 of the setter is fixed in position and rests on top of bushing B. The inner sleeve 2 is in threaded engagement 70 with the outer sleeve 1 and carries a central spindle sleeve 3 rotating and moving longitudinally in the outer sleeve 1. Between the spindle 3 and the sleeve 2 is a bearing 4 taking up the thrust between collar 5 on the 75 spindle 3 and the cup 9 at the upper end of sleeve 2. The cup 9 of sleeve 2 carries a hand wheel 6, whereby the sleeve 2 is rotated with relation to the sleeve 1 and moved longitudinally to raise or lower spindle 3. 80 Spindle 3 is independently rotated by hand wheel 7 fastened to its upper end.

The lower end of the spindle 3 is slotted as shown at 8 and within the slot are positioned arms 11 on pivot 10 and carrying 85 flanging rollers 12. Arms 11 are normally collapsed within the slot 8 by springs 13 bearing outwardly against the lower ends of the arms. Sliding centrally through spindle sleeve 3 is the rod 15 carrying a wedge 16 at 90 its lower end which acts when the rod is pressed downwardly to spread the flanging arms into operative position. To the upper end of rod 15 is fastened a rope 18 passing over pulleys 19 and counterweighted at 95 20 to sustain the weight of the setter. The rod 15 carries a collar 17 at its lower end engaging the upper end of slot 8 and holding the rod from withdrawal.

In the normal operation of the device the 100 rod 15 is held in its uppermost position by counterweight 20 leaving the setter and flanging arms 11 held collapsed within slot 8 by springs 13. The operator drives the bushing B into the hole in barrel A, and 105 then lowers the setter into the position shown in Fig. 1 with its spindle sleeve 3 extending within the bushing. The sleeve 2 has previously been moved to lower the spindle 3 110 sufficiently so that the flanging rollers will

take a position below the lower bushing edges as shown in Fig. 1 when spread by the downward movement of wedge 16 on central rod 15. When so spread, sleeve 2 is rotated by hand wheel 6 to raise the flanging rollers into tight contact with the bushing. Central rod 15 is released and sleeve 3 is rotated by hand wheel 7 and raised gradually by rotation of sleeve 2 by hand wheel 6 to flange and turn over the bushing B against the barrel. As the flanging operation progresses the flanging arms 11 move outwardly around their pivot so that the flanging rollers automatically follow the bead they are forming and increase their angle of thrust as the flanging operation increases. This prevents longitudinal compression of the bushing, or upsetting.

In operating the spindle 3 the relative amounts of rotating and raising movements can be controlled by the relative amount of rotation of hand wheels 6 and 7. In practice, hand wheel 6 is usually rotated slightly to produce a slight bend in the bushing 25 flange and then hand wheel 7 is rotated to carry this bend completely around the bushing, these operations being repeated successively until the flange is finally formed and spun up onto the barrel by rotation of the 30 hand wheel 7. The operator can tell by the resistance offered to the turning of hand wheel 6 when the flange is fully set. By reverse turning movement of hand wheel 6, spindle 3 is lowered and its flanging arms 35 carried out of engagement with the set bushing and collapsed within slot 8 by spring 13 so that the operator has only to lift the setter to remove it from the barrel.

In order to hold the setter in place on 40 the barrel, a stand 27 is provided comprising end pieces shaped to receive the barrel and connecting side pieces. Chains 26 and 28 are fastened to side pieces of the frame and extend upward around the barrel and 45 are adjustably fastened to the outer sleeve 1. The chain 26 has one of its links engaged by the lug 25 of pawl 24 adjustable in slot 22 of the arm 21 extending from sleeve 1. The bottom of slot 22 is serrated 50 as shown at 42 and is engaged by the point 43 of pawl 24. The upper part of slot 22 is undercut to form the overhanging ridges 23 engaging the body of pawl 24 when tipped by the tension of chain 26 and holding said pawl in contact with serrations 42. The chain 28 has one of its links engaged 55 by collars formed by a slot in web 32 extending across the periphery, winding drum 31 on shaft 30 rotating in bracket 29 on sleeve 60 1. Fastened to shaft 30 is the ratchet wheel 33 carrying the handle 35 and engaged by dog 34.

The rough adjustment of the chain length provided by dog 24 serves to center the 65 setter on the barrel in approximately vertical

position. The winding drum 31 engaging chain 28 allows both chains to be brought into tension by handle 35 to hold the sleeve 1 and the setter tightly in position on the bushing. The ratchet 33 and dog 34 hold the parts under tension during the flanging operation. In the operation of the holding means the barrel is positioned on the stand 27, the setter is lowered into position on the bushing, the proper link of chain 26 is placed over lug 25 of pawl 24 which is adjusted in proper position within the slot 22 to approximately center the setter in vertical position. Chain 28 is then caught in slot of capstan 31 and the handle 35 is moved down clockwise, as seen in Fig. 1, to draw the chains taut, dog 34 holding the handle 35 in its final position by engagement with ratchet 33.

In this way the barrel is held on its stand 85 and the fixed sleeve of the setter is pressed into tight engagement with the bushing B holding said bushing against rotation during the flanging operation. With the setter so held in proper position the operator is 90 free to devote his entire attention to the proper manipulation of the flanging spindle as above described and he may use both hands to turn wheels 6 and 7 simultaneously or in quick alternation until the flanging 95 and setting operation is complete.

The release of the holding means is easily accomplished by raising dog 34 and removing the chains 26 and 28 from engagement with lug 25 and capstan 30, respectively. 100 When so released, the setter is free to be lifted from the bushing and the barrel A can be taken from the stand.

It will thus be seen that there is provided a simple, easily portable apparatus, 105 which will hold the setter, barrel and bushing in proper relation. The setter prevents rotation of the bushing in the barrel and the flanging means is constructed to reach into the barrel and set the bushing with a minimum of attention on the part of the operator. The flanging rollers are easily positioned with relation to the bushing and when so positioned operate to gradually turn over the setting flange. The relative resistances 110 offered to the turning of wheels 6 and 7 inform the operator as to the character and extent of the flanging operation so that the relative movements of advance and rotation can be properly proportioned for each bushing. 115

It is apparent that other means may be used to hold the setter in place on the barrel or that special holding means may be dispensed with altogether and we do not 125 wish to confine the invention to the specific embodiments above described, but intend to include such modifications thereof as fall within the scope of the appended claims.

Having thus described our invention, we 130

declare that what we claim as new and desire to secure by Letters Patent, is:—

1. A bushing setting apparatus comprising a rotatable spindle carrying flanging means adapted to engage and flange the inner projecting end of a bushing inserted in a barrel, a clamping member adapted to engage the outer flange of the bushing, means holding the clamping member in fixed engagement with the bushing, a thrust bearing on the spindle, a sleeve between the thrust bearing and the clamping member having threaded engagement with the latter for effecting relative longitudinal movement between the flanging means and the clamping means, and means for rotating the flanging means independently of said clamping means and said sleeve to flange and set the bushing. 70
2. A bushing setting apparatus comprising a rotatable spindle carrying flanging means adapted to engage and flange the inner projecting end of a bushing inserted in a barrel, a clamping member adapted to engage the outer flange of the bushing, tension means encircling the barrel and connected to opposite sides of said clamping member for preventing rotation thereof and the bushing, a thrust bearing on the spindle, a sleeve between the thrust bearing and the clamping member having threaded engagement with the latter for effecting relative longitudinal movement between the flanging means and the clamping means, and means for rotating the flanging means independently of said clamping means and said sleeve to flange and set the bushing. 75
3. A bushing setting apparatus comprising a rotatable spindle, thrust arms pivoted at the end of said spindle and projecting upwardly and outwardly thereof, flanging rollers carried at the ends of said arms and adapted to engage and flange the inner projecting end of a bushing inserted in a barrel, a clamping member adapted to engage the outer flange of the bushing, means holding the clamping member in fixed engagement with the bushing, a thrust bearing on the spindle, a sleeve between the thrust bearing and the clamping member having threaded engagement with the latter for effecting relative longitudinal movement between the flanging means and the clamping means, and means for rotating the flanging means independently of said clamping means and said sleeve to flange and set the bushing. 80
4. A bushing setting apparatus comprising a clamp member for engaging and holding the bushing, a rotatable flanging means within the clamp member, means adapted to encircle a barrel for holding the clamp member in clamping position on the bushing by tension to prevent displacement and rotation of the clamp member during rotation of the flanging means, and means for moving said flanging means toward said clamp member to produce a flanging thrust independently of the clamping pressure. 85
5. A bushing setting apparatus comprising a clamp member for engaging and holding the bushing, a rotatable flanging means within the clamp member, means adapted to encircle a barrel for holding the clamp member in clamping position on the bushing by tension to prevent displacement and rotation of the clamp member during rotation of the flanging means, and means for moving said flanging means toward said clamp member to produce a flanging thrust independently of the clamping pressure. 90
6. A bushing setting apparatus comprising a clamp member for engaging and holding the bushing, a rotatable flanging means within the clamp member, means adapted to encircle a barrel for holding the clamp member in clamping position on the bushing by tension to prevent displacement and rotation of the clamp member during rotation of the flanging means, and means for moving said flanging means toward said clamp member to produce a flanging thrust independently of the clamping pressure. 95
7. A bushing setting apparatus comprising a clamp member for engaging and holding the bushing, a rotatable flanging means, and means adapted to encircle a barrel for holding the clamp member in clamping position on the bushing by tension to prevent displacement and rotation of the clamp member during rotation of the flanging means, said tension means being in part composed of means supporting the barrel in firm position. 100
8. The combination with a portable bushing setter for flanging bushings in barrels comprising means for pressing on the head of the bushing when inserted in the barrel, and rotatable means for flanging the inner end of the bushing within the barrel, of tension means connected to said setter and adapted to encircle the barrel for holding the setter in working position, said tension means being in part composed of means for supporting the barrel in firm position, including a chain or the like separably connected to said setter at one end for adjusting its length, and connected by a winding means at the other end to produce the desired tension. 110
9. The combination with a portable bushing setter for flanging bushing in barrels comprising means for pressing on the head of the bushing when inserted in the barrel, and rotatable means for flanging the inner end of the bushing within the barrel, of tension means connected to said setter and adapted to encircle the barrel for holding the setter in working position, said tension means being in part composed of means for supporting the barrel in firm position, including a chain or the like separably connected to said setter at one end for adjusting its length, and connected by a winding means at the other end to produce the desired tension. 115
10. The combination with a portable bushing setter for flanging bushing in barrels comprising means for pressing on the head of the bushing when inserted in the barrel, and rotatable means for flanging the inner end of the bushing within the barrel, of tension means connected to said setter and adapted to encircle the barrel for holding the setter in working position, said tension means being in part composed of means for supporting the barrel in firm position, including a chain or the like separably connected to said setter at one end for adjusting its length, and connected by a winding means at the other end to produce the desired tension. 120
11. The combination with a portable bushing setter for flanging bushing in barrels comprising means for pressing on the head of the bushing when inserted in the barrel, and rotatable means for flanging the inner end of the bushing within the barrel, of tension means connected to said setter and adapted to encircle the barrel for holding the setter in working position, said tension means being in part composed of means for supporting the barrel in firm position, including a chain or the like separably connected to said setter at one end for adjusting its length, and connected by a winding means at the other end to produce the desired tension. 125
12. The combination with a portable bushing setter for flanging bushing in barrels comprising means for pressing on the head of the bushing when inserted in the barrel, and rotatable means for flanging the inner end of the bushing within the barrel, of tension means connected to said setter and adapted to encircle the barrel for holding the setter in working position, said tension means being in part composed of means for supporting the barrel in firm position, including a chain or the like separably connected to said setter at one end for adjusting its length, and connected by a winding means at the other end to produce the desired tension. 130

end of the bushing within the barrel, of tension means connected to said setter and adapted to encircle the barrel for holding the setter in working position, said tension means being in part composed of means for supporting the barrel in firm position, including a chain or the like connected at both ends to said setter, and means for tightening the chain to produce the desired tension.

10. The combination with a portable bushing setter for flanging bushings in barrels comprising means for pressing on the head of the bushing when inserted in the barrel, and rotatable means for flanging the inner 15 end of the bushing within the barrel, of tension means connected to said setter and adapted to encircle the barrel for holding the setter in working position, said tension means being in part composed of means for supporting the barrel in firm position, including a chain or the like, an adjustable ratchet pawl for separably engaging one 20 end of the chain and the setter to resist tension, and a winding ratchet engaging the other end of the chain for applying the desired tension.

11. A bushing setting apparatus comprising a clamp member adapted to engage and hold the bushing, rotatable flanging means 25 within the clamp member adapted to en-

gage and flange the inner end of the bushing, a barrel support, and adjustable link members respectively connecting opposite sides of said clamp member and the ends of said support for holding the clamp member 35 against displacement and rotation during rotation of the flanging means.

12. A bushing setting apparatus comprising a clamp member adapted to engage and hold the bushing, rotatable flanging means 40 within the clamp member adapted to engage and flange the inner end of the bushing, a barrel support, a rack connected at one side to the clamp member, a chain connected at one end to said support and having an adjustable pawl coöperating with said rack, a capstan connected to the opposite side of the clamp member, and a second chain connected at one end to said support and adjustably connected to said capstan, whereby 45 tightening of said chains holds the clamp member and bushing against rotation during rotation of the flanging means.

In testimony whereof we affix our signatures in presence of two witnesses.
